United States Patent Office.

L. D. PARSONS, OF TREMONT, NEW YORK.

Letters Patent No. 95,930, dated October 19, 1869.

IMPROVEMENT IN WIND-WHEEL PUMPS.

The Schedule referred to in these Letters Patent and making part of the same.

To all whom it may concern:

Be it known that I, L. D. PARSONS, of Tremont, in the county of Westchester, and State of New York, have invented a new and useful Improvement in Windmills for Pumping; and I do hereby declare that the following is a full, clear, and exact description thereof, which will enable others skilled in the art to make and use the same, reference being had to the accompanying drawings, forming part of this specification.

This invention relates to new and useful improvements in windmills for pumping water, and for other purposes; and

It consists in so constructing the machine, and applying the power, that the plunger of the pump is raised and liberated periodically, and water forced upward by the weight of the plunger bearing upon its surface.

It also consists in so arranging the machine that a vane is dispensed with; and

Lastly, in the manner of constructing the wind-wheel, as will be hereinafter more fully described.

In the accompanying drawings—

Figure 1 represents a sectional side elevation of the machine, showing its construction and manner of operation.

Figure 2 is a detached view, showing the back side of the wind-wheel, as completed.

Similar letters of reference indicate corresponding parts.

This windmill is elevated from the ground on four (more or less) posts or supports A, which rest upon the base B, upon the top of which supports is placed the circle B', upon which the traversing-wheel of the mill revolves on the rollers C.

D is the traversing-wheel, to the top of which the frame E, which supports the mill-shaft F, is attached.

G is a drum-sleeve on the shaft F, which couples with the fast collar H on the shaft.

I is a flange on the drum, and J is a groove in its back end.

K is the guide-rod.

L is an adjustable collar on the guide-rod.

M is a tripping-lever, which is hinged at N.

The rod K is attached to its outer end, as seen in the drawing.

Its hinged portion engages with the groove J in the drum G, as seen.

O is a rope or cord, attached to the flange I, and P is a weight, attached to the lower end of the rope.

The rod K passes through the weight, and guides it in its rise and fall.

As seen in the drawing, the drum G is coupled with the shaft by means of the collar H.

Now, as the drum is revolved by the shaft, the rope O will be wound upon the drum, and the weight P will be raised on the rod K.

When the weight strikes the end of the lever M, it will raise the end of the lever, the effect of which is to throw back and uncouple the drum.

When thus uncoupled, the weight will descend by its own gravity, till it strikes the collar L on the rod. The effect of this is to force down the rod and lever M, and to couple the drum to the shaft again.

The method of operation, in raising water, is as follows:

U is a belt-rope or wire, which is attached to the weight P, and passes therefrom down through the base B, and under a pulley, (when the windmill is remote from the well or cistern,) and extended to a point over the cistern, where it passes over another pulley, from which it descends, and is attached to the plunger of a pump.

When the weight P is raised, the plunger will be raised, and water will be forced up, as the plunger descends by its own gravity or by displacement.

By this arrangement the windmill may be placed in any convenient location, and the connection made, and water raised, by simply extending a wire horizontally from the mill to the cistern.

The quantity of water so raised, and the height or distance it may be carried, will, of course, depend upon the dimensions and power of the machine.

R represents the centre-disk of the wind-wheel, which is fast on the end of the shaft, and to which the arms S of the wings T are secured in the manner shown in the drawing.

Unlike ordinary windmills, the wings face inward, and receive the wind from the direction indicated by the arrow.

This arrangement enables me to dispense with a vane to the mill, thus diminishing the expense, and rendering its motion more steady and uniform.

Having thus described my invention,

I claim as new, and desire to secure by Letters Patent—

1. The combination of a reciprocating weight, P, with a pump-rod, K, having an eye at the top and another at L, whereby, as the weight strikes the top g, the rod is raised, and when it strikes the bottom one, it is depressed, all as shown and described.

2. The combination of a winding-spindle, G, loose upon its shaft, and alternately locked and unlocked, with a cord, O, and weight, P, whereby the rod K is raised by mechanical power, but depressed by gravity, in the manner set forth.

3. The combination of the rod K, reciprocating

weight P, and lever M, arranged and operated as described, to ship and unship the clutch-sleeve G, in the manner described.

4. The combination of the shaft F, clutch-collar H, clutch-sleeve G, lever M, cord O, and weight P, with the lugged rod K, to displace the water and cause its elevation, as set forth.

5. The combination of the shaft F with a wind-

driver, whose wings T face inward, as specified, whereby a vane is rendered unnecessary.

6. The subject-matter of fourth clause, in combination with the wind-driver, as and for the purpose specified.

Witnesses:

FRANK BLOCKLEY,
ALEX. F. ROBERTS.

L. D. PARSONS.
